UNITED STATES PATENT OFFICE.

LUDWIG KÜHN, OF BERLIN-CHARLOTTENBURG, GERMANY, ASSIGNOR TO WESTINGHOUSE ELECTRIC & MANUFACTURING COMPANY, A CORPORATION OF PENNSYLVANIA.

CONNECTION FOR PRODUCING OSCILLATIONS WITH VACUUM TUBES.

Application filed August 26, 1921. Serial No. 495,736.

(GRANTED UNDER THE PROVISIONS OF THE ACT OF MARCH 3, 1921, 41 STAT. L., 1313.)

To all whom it may concern:

Be it known that I, LUDWIG KÜHN, a subject of the State of Germany, residing at Berlin-Charlottenburg, Germany, have invented certain new and useful Improvements in Connections for Producing Oscillations with Vacuum Tubes (for which I have filed applications as follows: Germany, filed Sept. 27, 1917, now German Patent No. 310,152; Germany, filed April 26, 1919, No. 76,903; Argentine, filed Dec. 9, 1920, now Patent No. 17,742; Belgium, filed July 9, 1920, now Patent No. 289,103; Bolivia, filed Febr. 2, 1921, now Patent No. 155; Brazil, filed Jan. 7, 1921, now Patent No. 13,196; Brit. India, filed Nov. 25, 1920, now Patent No. 6421; Canada, filed Nov. 17, 1920, No. 248,295; Denmark, filed June 30, 1920, No. 1971; Great Britain, filed July 7, 1920, now Patent No. 148,803; Finland, filed Sept. 29, 1920, now Patent No. 8724; Holland, filed Mar. 5, 1920, No. 14,205; Italy, filed July 6, 1920, No. 292/60; Japan, filed Oct. 1920, No. 61,497; Norway, filed June 30, 1920, No. 21,173; Rumania, filed Dec. 22, 1921, No. 751; S. Africa, filed Nov. 20, 1920, now Patent 1280; Sweden, filed Jan. 2, 1920, No. 8 and July 12, 1919, No. 3227; Switzerland, filed Oct. 18, 1920, now Patent No. 95,307; Czechoslovakia, filed July 9, 1920, No. P 5610 and July 27, 1922, No. 3447; Hungary, filed Aug. 27, 1920, No. H. 6560; Chile, filed Jan. 6, 1921; Spain, filed Mar. 24, 1920, now Patent No. 73,107; Australia, filed July 12, 1920, No. 16,613; France, filed Dec. 2, 1920, now Patent No. 531,894; Venezuela, filed Jan. 28, 1921, now Patent No. 525), of which the following is a specification.

The new connection is illustrated in Figure 1, Fig. 2 shows a tube for producing oscillations and Fig. 3 illustrates a modified form of construction.

In Fig. 1, 1 is the vacuum tube, 2 its incandescent cathode, 3 the grid, 4 the anode. The anode-circuit is from the anode, through the battery 5 with condenser 6 in parallel, through a coil 7, to the incandescent cathode 8. Coil 7, may, if desired, be variable. The antenna 9 is connected to the coil 7 through a variometer 10, or it may be coupled inductively with it and be also provided with a condenser 11. The grid 3

is excited by a completely independent oscillation circuit consisting of coil 12 and condenser 13.

The novelty of the connection consists in there being no inductive or capacitative coupling between the anode circuit and the oscillation system of the grid. As compared with the present state of the art, it represents novelty in that hitherto it has been considered necessary to provide a return coupling between the anode circuit which conducts the strengthened oscillations and the grid circuit which serves to control and maintain the oscillations. Whereas the known connections have the disadvantage of being suitable either only for the production of very rapid or only for the production of relatively slow oscillations, it is possible with the present connection to produce an almost unlimited range of wave-lengths and at the same time to work with absolute efficiency. Of first importance, however, is the entire absence of auxiliary oscillations. The wave-length produced is on the other hand completely one-wave, which is, I believe, the explanation of the excellent degree of efficiency.

To prevent auxiliary oscillations it is important to couple the antenna with the anode circuit, preferably conductively. Various wave-lengths as desired are secured by adjusting the grid circuit to the desired wave and so tuning the antenna that a measuring instrument therein gives maximum deflection.

In order to tune the two circuits as quickly as possible and as a unit, the tuning devices, for these circuits or the parts of the mechanism which serve them may be made mechanically interdependent. By this means, it is possible simultaneously, and, if desired, with a common operating means, to bring the circuits to identical frequency. In the case where these circuits are coupled, such coupling can, if necessary, be brought into mechanical dependence upon the tuning devices of the circuits so that the coupling may also be simultaneously changed with the syntonization of the circuits. Under these conditions the circuits can be synchronized continuously, whereas the coupling is changed by steps. Similarly, the syn-

tonization in the circuits can be changed by steps.

If such an apparatus for producing oscillations is used for heterodyning, it is possible to adjust the tuning devices of the heterodyne in such a way that a certain change in the tuning of the generator would correspond to a similar change in the receiver in such a manner that the frequencies for which the receiver and the generator are respectively tuned lie within practical range for producing beats. It is then possible to secure mechanical dependence between the tuning devices, the switch members, and the like, of the receiver, and those of the heterodyning generator, so that they can both be operated by a common element.

In Fig. 2 *r* represents a tube for producing oscillations, *s* its controlling circuit, *e* its energizing circuit, *a* the tuning means in the first, *b* the tuning means in the latter, which means are formed, by way of example, as variable inductors and condensers and are so disposed that they can be moved by a handle *h* upon a common shaft in such a way that both circuits are set to about equal frequencies.

Fig. 3 illustrates a form of construction, by way of example, which, in addition to the elements of Fig. 2, is provided with a coupling *k* adjustable by steps. All the electrical elements required for making the adjustments are, in this case also, operated by a single mechanical element *h*. It is understood, however, that the mechanical connections are not so disposed that a particular electrical adjustment corresponds to a given angle of rotation of the handle. The ratio of mechanical movement between the tuning devices and the common driving member *h* may, for example, be made to differ for the several tuning devices.

This result could be secured by the use

of sprocket wheels, skids, or the like, in place of differently geared drives. By the use of this invention, the same apparatus may be used either as a generator for sending or as a heterodyne device for receiving. The receiving circuit or the sending circuit may be connected by a common separable connector and the antenna when connected to the illustrated device has needs only to be tuned in the usual way.

Having now particularly described and ascertained the nature of my said invention and in what manner the same is to be performed, I declare that what I claim is:

1. In a vacuum-tube device, a tuned plate circuit, a tuned grid circuit, each of said tuned circuits including a variable inductor and a variable capacity and means, including a mechanical connection between said variable reactors, for simultaneously tuning both circuits.

2. In a vacuum-tube device, a plate circuit, a grid circuit, an adjustable coupling between said circuits, adjustable devices in each of the circuits for tuning the same and means for simultaneously changing the adjustment of each of said adjusting devices.

3. In a vacuum-tube device, a plate circuit, a grid circuit, an adjustable coupling between said circuits, adjustable devices in each of the circuits for tuning the same and means for simultaneously changing the adjustment of each of said adjusting devices, said means including a common actuator and a mechanical connection between said actuator and each of said adjustable devices, said mechanical connections affording different motion ratios, whereby both of said circuits and the coupling may be simultaneously adjusted to provide for the same frequency.

In testimony whereof I affix my signature.

DR. ING. LUDWIG KUHN.
